UNITED STATES PATENT OFFICE.

GEORGE P. BRAND, OF NEW YORK, N. Y.

SHEET-CENTRALIZING MECHANISM.

1,143,684.

Specification of Letters Patent. Patented June 22, 1915.

Application filed December 26, 1913. Serial No. 808,861.

To all whom it may concern:

Be it known that I, GEORGE P. BRAND, a citizen of the United States of America, and resident of New York, county of New York, 5 and State of New York, have invented certain new and useful Improvements in Sheet-Centralizing Mechanism, of which the following is a specification.

This invention relates to certain new and 10 useful improvements in sheet centralizing mechanisms for automatic musical instruments and it has for its objects among others to provide a simple, yet efficient, quick acting and positive mechanism by which the 15 perforated sheet is accurately and quickly centralized, regardless of the manner in which it is wound upon the music spool.

My principal aim is to compensate for all 20 inaccuracies in wind and from other causes, by means actuated positively by the music sheet and serving to positively and quickly centralize such sheet, such mechanism serving equally as well with sheets of greater or less width. I employ simultaneously moving 25 able members connected together to move in unison and engageable with opposite edges of the sheet and traveling with the same at all times in contact therewith, and constructed to control inlet and exhaust valves 30 by connection with means movable with said movable members.

Heretofore great trouble has been experienced and imperfect results attained by reason of the variations in width of the 35 music sheet as well as with the shrinkage of such sheets, which, in some instances, is nearly one-eighth of an inch, as the mechanisms usually employed on each side of the sheet for this purpose are not connected 40 with each other to work in unison and automatically simultaneously movable and always in contact with the edges of the sheet. Furthermore, the width of the sheet changes the normal relative positions of the parts. 45 By my improved mechanism the variation in the width of the sheet in no wise affects the normal relative positions of the parts constituting the centralizing mechanism, thereby admitting of more accurate results 50 and centralization with minimum movement.

I employ an inlet and an exhaust valve, both normally closed when the sheet is centralized, one of which only is open at a time, 55 a slight lateral movement of the sheet be-

ing sufficient to open one valve or the other without disturbing the remaining valve, and the valve thus opened is instantly closed when the sheet is again centralized, through connection with a pneumatic which, in turn, 60 when deflated, controls the lateral movement of the music spool in one direction, and when inflated, the spring moves it in the opposite direction.

In connection with the above I employ a 65 clutch device to hold the said pneumatic in the position last set by said centralizing mechanism, whereby if the operator ceases playing, the sheet remains centralized and when he resumes playing there are no false 70 notes sounded, as would be the case if the sheet had to be again centralized. Without such clutch device, the pneumatic would become inflated when playing ceased.

In connection with the above-mentioned 75 centralizing mechanism, I sometimes employ a take-up roll having adjustable flanges for keeping the paper thus centralized from lateral movement as it is wound upon said take-up roll. This latter may be manual or 80 automatic and in some cases may be omitted entirely, but when employed, it relieves the centralizing mechanism of the work of correcting the lateral movements of the sheet after being wound upon the take-up roll, 85 and, consequently, insures even winding of the sheet on the take-up roll, and thereby insures perfect parallelism in the travel of the sheet from the music spool to the take-up roll and prevents wrinkling and, hence, 90 avoids liability of such distortion of the sheet as to cause sounding of false notes and injury to the sheet by breakage thereof. I may also sometimes employ a governor to lighten the tension in the exhaust chamber 95 so that the valve controlling the exhaust port is opened with less effort on the part of the music sheet.

The present invention, while shown as applied to an automatic musical instrument, 100 may be used with equally beneficial results in connection with other devices, such as automatic letter writing machines and the like, and, therefore, the invention is not restricted to the particular use to which it is herein 105 shown as applied.

Other objects and advantages of the invention will hereinafter appear and the novel features thereof will be particularly pointed out in the appended claims.

The invention is clearly illustrated in the accompanying drawings, which, with the numerals of reference marked thereon, form a part of this specification, and in which—
5 Figure 1 is a front elevation of my present invention showing such parts of an automatic musical instrument as are necessary to the proper understanding of my present invention, with the latter applied thereto.
10 Fig. 2 is a top plan of Fig. 1 with portions broken away. Fig. 3 is a rear elevation. Fig. 4 is a section on the line 4—4 of Fig. 6 looking in the direction of the arrows. Fig. 5 is a vertical section at right angles 15 to Fig. 4, as on the line 5—5 of Fig. 6. Fig. 6 is a top plan of the valve chest and governor with portions broken away. Fig. 7 is an enlarged perspective detail of the sheet contacting members and carriage 20 mechanism therefor. Fig. 8 is a similar view of a modified form. Fig. 9 is a detail of the clutch mechanism showing the pneumatic inflated. Fig. 10 is a similar view showing the pneumatic deflated. Fig. 11 is 25 an enlarged detail partly in section and partly in elevation illustrating the action of the clutch. Fig. 12 is a detail in section on the line 12—12 of Fig. 7. Fig. 13 is a face view of the rotary valve member of the 30 flange actuating mechanism.

Like numerals of reference indicate like parts throughout the several views.

Various parts of the player are herein illustrated for the purpose of making clear 35 the application and operation of the parts constituting my present invention, but it is to be understood that such parts are shown merely by way of illustration and a detailed description thereof is not necessary, nor is 40 the invention restricted to use in connection with such particular construction of player except as hereinafter specified.

Referring to the drawings, 1 designates 45 a tracker bar which in operation is relatively fixed, although normally capable of adjustment endwise for obvious purposes. It is mounted in the uprights 2 rising from the base 3 of the music box.

4 is the take-up roll and 5 the music spool 50 on which the usual perforated sheet 6 is wound and from which it is unwound while playing and wound upon the take-up roll 4 in the usual manner, it being understood, of course, that motion is imparted to the 55 parts through the medium of a motor and transmission mechanism (some of the latter of which is illustrated in Figs. 1 and 2) in any well known or usual way, the present invention not pertaining to such operating 60 or transmission mechanism, except as hereinafter specified.

The music roll or spool 5 is journaled, as shown, on the spindles 7 and 8, the spindle 8 being of the usual well known spring 65 pressed variety and the spindle 7 being end-

wise movable in its bearings for a purpose now to be described. The spindle 7 is extended through the support 2 and its outer end 9 mounted in the outer arm 10 of a U-shaped support 11, the other arm of which 70 is adapted to be attached to the upright 2 in any well-known way. The outer end 9 of the spindle 7 bears against the lever 12 pivotally mounted at one end, as at 13, in a lateral arm 14 on the support 2. The free end 75 of this lever 12 is disposed between buttons 15 adjustable upon the screw-threaded end 16 of a rod 17 which extends parallel with the music roll and has its other end attached in any suitable manner, as at 18, to the movable board 19 of the pneumatic 20, as seen best in Fig. 3. Normally the spring of the spindle 8 tends to force the music roll or spool toward the right in Fig. 1, thus forcing the outer end 9 of the spindle 7 against 80 the lever 12. Now, if the pneumatic 20 is deflated, the rod 17 pulling upon the lever 12 and the latter bearing against the extended end 9 of the spindle 7 forces the music spool and, consequently, the music 85 sheet thereon to the left in Fig. 1. Now, if the pneumatic is inflated, the spring 21 of the pneumatic 20 forces the movable member 19 of the pneumatic in the opposite direction or toward the right in Fig. 1, carrying with it the rod 17 and, consequently, the lever 12, when the spring of the spindle 8 serves to force the music spool and, consequently, the music sheet to the right in 90 Fig. 1.

100 The controlling mechanism comprises two members mounted to contact with opposite edges of the sheet during its movement over the tracker and these members 22 are so mounted and arranged as to move simultaneously, being connected together for that purpose, so that they will move toward each other and from each other to accommodate music spools of less or greater width. In Figs. 7 and 8 I have shown two different 105 forms of mounting of these members 22.

110 Referring first to Fig. 7, 23 are blocks or supports secured in any suitable manner to the ends 2, 2 of the music box behind the tracker bar. In each block 23 there is 115 mounted for swinging movement an arm 24, the lower end of which extends substantially horizontally, as seen at 25, and upon each horizontal portion there is mounted a bearing 26, seen best in Fig. 12, around which is 120 coiled and to which is affixed by solder or any other suitable means, the coil 27 of the arm 28 carrying the member 22. This arm 28 is extended beyond its point of connection with the bearing 26, as seen at 29, the two 125 horizontal extensions 30 being overlapped and united in any suitable manner, so as to permit of the requisite sliding movement of said overlapped ends, as the members 22 are moved to and from each other. Any suit- 130

able form of connection may be employed which will permit of this result. In the present instance, one of the flattened ends 31 is shown as provided with a longitudinal slot 32 in which works a pin 33 carried by the other flattened portion, as seen clearly in Fig. 7.

For the purpose of holding the two bearings 26 in fixed relation to each other, I 10 provide the rod 34 which extends substantially parallel with the tracker bar and has its ends flattened, as at 35, and loosely embracing the horizontal portions 25 of the swinging members 24 so as to have pivotal 15 movement thereon. This rod 34 serves to so connect the parts that the members 22 move in unison simultaneously toward and from each other to compensate for different widths of sheets. When the music sheet de- 20 viates to the right or left in its travel over the tracker bar, the movement of the members 22, caused by such deviation, moves the rod 34 to the right or to the left owing to the manner in which the parts are mounted 25 upon the swinging arms 24.

Mounted upon the rod 34 near one end is a coupling 36 affixed to the said rod in any suitable manner. Adjustably mounted in this coupling 36 by means of a set screw 30 37, or any other well-known means, is an arm 38 provided at its outer end with an eye or analogous means 39, by which it is loosely engaged over an arm 40 extending at right angles to said arm 38, as seen in Fig. 1, 35 whereby said arms 38 and 40 are coupled together.

Secured to one of the members 30 is a coupling 41 in which is adjustably held by means of a set screw or the like 42 an arm 43 designed for attachment to the rewind mechanism so that when the sheet is rewound the member 43 will be moved in the direction of the arrow in Fig. 7, throwing up the point or connection of the rods 30 45 and throwing the members 22 outward away from the sheet.

In Fig. 8 I have shown another form of mechanism for accomplishing substantially the same purpose. In this figure, 23^a are blocks designed to be secured to the inner faces of the ends 2 of the music box, being the equivalents of the blocks 23 shown in Fig. 7. The members 22^a, which are designed for contact with the edges of the sheet similar to the members 22 in Fig. 7, are carried by the arms 44 which have the outwardly extended horizontal portions 45 and the downwardly extending portions 46, said downwardly extending portions 46 50 joining the horizontal portions 47, each of which is pivotally mounted, as at 48, upon the lower end of a swinging link or the like 49, the upper end of which is pivotally mounted, as at 50, upon the block 23^a. The horizontal members 47 are extended form-

ing the arms 51, the adjacent ends of which overlap and, as shown in Fig. 8, are flattened, as seen at 52, and connected by a pin or the like 53 fast upon one member 51 and received within an opening in the flattened portion of the other member. The vertical portion 46, shown at the left of Fig. 8, has pivotally received therein, as at 54, one end of a rod 55, the other end of which is provided with an eye or the like 56 which is adapted to engage the arm 40 in a manner similar to the engagement of the eye 39 with such rod, as seen in Fig. 1.

Fast upon the horizontal member 44 at the left of Fig. 8 is a coupling 57 in which is adjustably held by means of a set screw or the like 58, one end of a rod 59 which is designed for attachment to the rewind mechanism and serving the same purpose as the arm 43 shown in Fig. 7.

The members 30-30 are guided in their movement and held against undue motion horizontally transversely of the length of the tracker bar by means of a loop or the like 60, as seen in Figs. 1 and 7, said loop 90 depending from the rod 34, as seen clearly in Fig. 7.

The rod 40, hereinbefore described, extends horizontally from a pendent rod 61, see Fig. 4, which is pendent from a pivot 95 62 fulcrumed at its ends in the parallel arms 63 of a U-shaped member 64 secured to one side of a block 65 secured to the valve chest 66, as seen clearly in Figs. 4 and 6. The pivot 62 is, by preference, mounted on knife 100 points so as to reduce friction and avoid lost motion.

The valve chest 66 has a chamber 67 which is connected by a tube 68 with the pneumatic 20, as seen best in Fig. 3. This 105 constitutes the exhaust from the pneumatic. The valve chest 66 has another chamber 69 which is connected with the atmosphere by a passage 70, as seen clearly in Fig. 4.

71 is a tube connecting the pneumatic 20 110 with the passage 72 of the valve chest and through the passage 73 and the port 74 with the chamber 69 and through the same and port 70 with the atmosphere. The port 74 is controlled by a valve 75, as seen in Figs. 115 4 and 5. The tube 71 constitutes the inflation tube of the bellows 20.

The chamber 67 connects by port 76 and passage 77 with the governor or regulating pneumatic 78, as seen clearly in Fig. 4. The 120 port 76 is controlled by a valve 79. The valves 75 and 79 are normally held to their seats by very delicate springs 80, as seen in Figs. 4 and 5. The valves 75 and 79 are guided in their movements to and from their 125 seats by the push rods 81, seen in Figs. 4 and 5, which enter the said valves, as indicated in said Figs. 4 and 5, these push rods having interposed between their ends the flattened end 82 of a lever arm 83 movable 130

with the pivot 62 hereinbefore described. As seen in Figs. 4 and 5, this flattened end of the lever arm 83 is disposed within a bore 84 in the body of the valve chest 66.

5 85 is a tube connecting the throttle port 86 of the governor pneumatic 78 with the operating tension through the T or coupling 87, as seen clearly in Fig. 3. The throttle port 86 is controlled by a valve 88 carried 10 by the movable member 89 of the said controlling pneumatic 78, as seen in Fig. 4.

The governor or controller valve 78 is provided with a bleed 90, as seen in Fig. 4.

I sometimes employ in connection with 15 the pneumatic 20, a clutch mechanism to retain said pneumatic 20 in the position in which it is left when the playing ceased, that is, if when the operator ceases playing the pneumatic 20 is, for instance, about one-half inflated, it will be immediately locked in such condition automatically until playing is resumed. This insures perfect registration upon resuming playing. Without the employment of the clutch mechanism, 20 as soon as the playing ceased, the paper would be liable to move with the roll laterally until the pneumatic 20 is fully inflated, causing non-registration of the perforations of the music sheet with those of the tracker 25 bar. Consequently, there would be improper sounding of the notes until the sheet was again centralized. This clutch mechanism comprises a pneumatic 91 mounted upon the pneumatic 20, as seen in Figs. 1, 2, 3, 9 and 30 10, and a pivotally mounted member 92 movable on a fulcrum 93 held in a suitable support 94, one end being provided with an opening 95 and the other end disposed between a spring 96 and an adjustable button 40 or bumper 97 carried on the movable member of the pneumatic 91, as shown clearly in said Figs. 1, 2, 3, 9 and 10. On the other member of the pneumatic 20 is a rod 98 extending in the direction of the movement of 45 the pneumatic in operation, which rod 98 is movable through the opening 95 of the pivoted member 92. The construction is such that when the members 92 and 98 are disposed at right angles to each other, freedom 50 of movement of the parts is permitted, but when the parts assume a position other than at right angles, as indicated by full lines in Fig. 11, the member 98 is bound by the diametrically opposite corners of the walls 55 of the opening 95 in the member 92 and clutched thereby, so that the parts are held in whatever position they may then assume, thus locking the pneumatic 20 in whatever position it may be found when the playing 60 ceases and the pneumatic 91 is inflated as shown in Fig. 9.

The above described mechanism constitutes my present improvement in the means for centralizing the paper passed over the 65 tracker bar. In some cases I may provide,

in addition to the above, means whereby the music sheet is assured of being wound evenly upon the take-up spool, after being centralized by the aforescribed mechanism. This mechanism embodies the mov- 70 ably mounted flanges 99 on the spindles of the take-up spool 4. They are moved back and forth on said spindles through the medium of the arms 100, one upon each spindle and forked or otherwise formed to 75 press against the hubs of the flanges, as seen clearly in Fig. 1. The flanges are moved in the opposite direction by the springs 101 of any well-known or preferred construction. These arms are connected at the back 80 of the music box by having their horizontal portions 102 united in any suitable manner, the said arms being pivotally mounted at their angles, as at 103, upon some suitable support, as seen in Fig. 3. The pin 104 85 connecting the adjacent ends of these members 102 has mounted thereon one end of a link 105, the other end of which is connected in any suitable manner with an arm 106 on the movable member 107 of a pneu- 90 matic affixed to the back 108 of the music box, all as clearly shown in Fig. 3.

109 is a tube designed to be connected with the action chest or any other part of the player. This tube 109 is connected with 95 a coupling 110 and is designed to supply the operating tension for the pneumatic 91 and the controlling governor 78, as seen in Fig. 3, as well as supplying air to the valve chest 111.

112 is the tube supplying air tension to the pneumatic 91 and 113 is the tube supplying air tension to the said chest 111.

114 is the tube supplying air tension to the re-wind pneumatic 115.

116 is the tube connecting the diaphragm chamber of the valve chest with the controlling valve port on the rotary valve member 117.

The valve chamber of the valve chest 111 110 is connected by passage 118 with the interior of the pneumatic 107, as indicated by dotted lines in Fig. 3.

With the parts constructed and arranged substantially as hereinbefore described, the 115 operation, briefly stated, is as follows. When the music sheet, wound upon the music spool and passed over the tracker bar and attached to the take-up roll 4, is first placed upon the machine between the flanges 120 of the music spool and the flanges 99 of the take-up roll, the edge contacting members 22 contact with the opposite edges of the sheet, the said members being forced farther apart according to the width of the 125 paper, the arms 30 being raised. They are shown in Fig. 1 as at their lowermost limit and, consequently, the members 22 are set for the width of paper. Now, if in this position the music sheet deviates to the left, 130

it moves the left hand edge contacting member 22 to the left, by reason of pressure thereagainst and this through the medium of the swinging members 24 and the connecting rod 34 moves the right hand edge contacting member 22 also to the left. During this movement of the parts, the rods 30 remain in the same position, the rod 34 being movable upon the horizontal portions 10 25 independent of the movement of the connections of the rods 30 with the bearings 26. When the paper is centralized, the members 22, 22, 34 and 30 constitute practically a rigid structure movable as a whole upon 15 the swing arms 24. This movement to the left carries with it the arm 38 which, by reason of the engagement of its eye 39 with the rod 40, causes the lever 83 to move slightly on its fulcrum so that its flattened 20 end contacts with the push rod 81 of the inflating valve 75, thus removing the valve from its seat against the tension of its spring, whereupon atmospheric air from the chamber 69 passes through the port 74 25 and the passages 73 and 72 to the tube 71 to the pneumatic 20, thereby inflating the pneumatic 20 and through the medium of the rod 17 moves the rod 12 to the right in Fig. 1, allowing the extended end 9 to 30 be pushed with the music spool through the medium of its spring spindle 8 to the right, immediately allowing the valve 75 to close which returns the lever 83 to its former position and centralizes the music 35 sheet. If the music sheet now moves to the right, it moves the right hand edge contacting member 22 to the right, by reason of pressure thereagainst and this, through the medium of the swinging rods 24 and 40 the connecting rod 34, moves the left hand edge contacting member 22 also to the right, it being understood that the structure composed of said members 22, swinging arms 24, rods 30, 30 and the connecting rod 34, 45 moves as a whole.

From the above it will be readily seen that a very slight movement of the music sheet will change the normal position of the valve 75 or 79 and thereby quickly return 50 the sheet to centralized position as there is no lost motion between said valves and the sheet. It will also be noted that the movement of the music sheet is multiplied, that is, the contact end of the lever 83 with the 55 push rods 81, has at least twice the movement that the rod 40 has, so that but little movement of the music sheet is required to move one valve or the other from its seat. In neutral position the flattened end of the 60 rod 83 is in close contact with the adjacent ends of the two push rods 81, and at this time the two valves are seated, the outer ends of the push rods 81 carrying said valves being in contact with the bottoms of the

holes in the outer ends of the valves, so that 65 there is no lost motion at these points either.

The music sheet is kept from lateral movement on the take-up spool by the movable flanges 99 in the following manner:—at every revolution of the take-up spool 4 the 70 rotary valve member 117 carried by one of the spindles thereof arrives at a point where its opening 119 coincides with a port 120 in the fixed member 121, with which port connects the tube 116 already described and 75 shown in Fig. 3, and which communicates with the diaphragm chamber of the valve chest 111. Atmospheric air admitted through this opening 119 causes the collapse of the pneumatic 107 through the valve 80 chest 111 which is of a well known construction, which, through the medium of the arm 106 and link 105, causes a movement of the rods 102 so as to actuate the arms 100 and move the flange 99 inward against the 85 edges of the music sheet. As soon as the rotary member 117 moves so that its opening 119 no longer coincides with the port 120 in the fixed member and, consequently, the latter is closed, the pneumatic 107 is 90 inflated and the flanges 99, by means of the springs in their spindles, are forced outward.

Modifications in detail may be resorted to without departing from the spirit of the invention, or sacrificing any of its advantages. 95

What is claimed as new is:—

1. Sheet-contacting means connected together and mounted to move in unison in the same or opposite directions at all times in 100 contact with the edges of a music sheet.

2. Sheet-controlling means connected together and mounted for movement in unison in the same or opposite directions at all times in contact with the edges of a music 105 sheet.

3. Sheet-engaging means mounted for engagement with the opposite edges of a music sheet at all times, swinging supports therefor, and means actuated by movement of 110 said supports for centralizing the sheet.

4. Means coöperating with a music sheet for contact therewith at all times, movable means moving therewith in unison in opposite directions, and means actuated by said 115 movable means for centralizing the music sheet.

5. Means coöperating with a music sheet for contact therewith at all times, movable means acting in unison to move said means 120 in both directions, and means actuated by said movable means for centralizing the music sheet.

6. Means coöperating with a music sheet, movable means connecting said means and 125 acting in unison therewith, and means coöperating with the first-named means for centralizing the music sheet.

7. Sheet-engaging means, at all times engageable with the edges of a music sheet swinging members by which they are carried, and means connecting said swinging members to cause them to move in unison. 65
8. Sheet-engaging means, at all times engageable with the edges of a music sheet swinging members by which said means are carried, and means connecting said means to move the same in opposite directions. 70
9. Sheet-engaging means, swinging members by which the same are carried, means connecting the said means permitting them to move in unison in opposite directions, and means connecting said members confining their movement in unison in the same direction. 75
10. Sheet-engaging means, swinging members carrying the same, means connecting said means permitting them to move in opposite directions, means connecting said members confining their movement in unison in the same direction, and sheet-centralizing means actuated thereby. 80
11. Sheet-engaging means, movable members carrying the same, means connecting and permitting movement of said means in unison in opposite directions, and means confining the movement of said members in unison in the same direction. 85
12. Sheet-engaging means, movably mounted supports therefor, connections permitting the movement of the said means in unison in opposite directions, and means connecting said supports and causing the same and the said means to move as a whole when one is moved. 90
13. Sheet-engaging means, pivotally mounted to move in unison in opposite directions, valves, and means for moving said valves, said valve-moving means being operatively connected with said sheet-engaging means. 95
14. Sheet-engaging means, pivotally mounted to move in unison in opposite directions, valves controlled by said means, and sheet-centralizing means controlled by said valves. 100
15. Sheet-engaging means pivotally mounted, means for moving them in unison in opposite directions, valves actuated by movement of said means, and pneumatic-actuated means controlled by said valves. 105
16. Means coöperating with a music sheet, valved, means controlled thereby, a pneumatic controlled by said last-named means, coöperating selector mechanism and a clutch embodying coöperating members both of which are carried by said pneumatic for automatically locking said pneumatic against movement when playing ceases. 110
17. Means coöperating with a music sheet, valved means controlled thereby, a pneumatic controlled by said last-named means, coöperating selector mechanism and a clutch embodying coöperating members both of which are carried by said pneumatic for automatically locking said pneumatic against movement when playing ceases. 115
18. Means coöperating with a music sheet, a pneumatic controlled thereby, coöperating selector mechanism and a clutch comprising coöperating members both carried by said pneumatic and acting to automatically positively lock the pneumatic when playing ceases and to automatically unlock the same when playing is resumed. 120
19. Means coöperating with a music sheet, movable means moving therewith, means actuated by said movable means for centralizing the music sheet, and means for automatically keeping the sheet from lateral movement upon the take-up spool. 125
20. Means coöperating with a music sheet, pneumatic means controlled thereby for centralizing the sheet, and pneumatic means for keeping the sheet centralized upon the take-up spool. 130
21. Movably mounted means coöperating with a music sheet, pneumatic means controlled thereby for centralizing the sheet, and pneumatic means for keeping the sheet centralized upon the take-up spool. 135
22. Pneumatic controlling means, and means acting to automatically positively lock the same when playing ceases and to automatically unlock the same when playing is resumed, said last-named means embodying interengageable friction members mounted upon a common carrier. 140
23. Sheet centralizing mechanism, a pneumatic, and automatic interengaging friction members carried by said pneumatic for locking the same against movement. 145
24. Sheet centralizing mechanism, a pneumatic, and pneumatically actuated positive locking means therefor movable therewith to hold the same at any predetermined point. 150
25. Sheet centralizing mechanism, a pneumatic, and a pneumatically controlled clutch mechanism movable with the pneumatic for positively holding the latter against inflation. 155
26. Sheet centralizing mechanism, a pneumatic, and a pneumatically controlled clutch mechanism movable with the pneumatic for positively holding the latter against inflation and permitting it to be automatically deflated. 160
27. In a device of the class described, sheet-contacting means pivotally mounted to move in unison in the same or opposite directions and valves normally seated and laterally removed from their seats by movement of said sheet-contacting means. 165
28. In a device of the class described,

sheet-contacting means mounted to move in unison in the same or opposite directions, valves normally seated and laterally removed from their seats by movement of said sheet-contacting means, and a governor for controlling atmospheric pressure upon said valves.

Signed by me at Washington, D. C., this 20th day of December 1913.

GEORGE P. BRAND.
